DESIGN FOR A CORN SLITTER

Carolyn R. Hanchett, Falls Village, Conn.

Application September 23, 1936, Serial No. 64,976

Term of patent 3½ years

To all whom it may concern:

Be it known that I, Carolyn R. Hanchett, a citizen of the United States, and residing at Falls Village, in the county of Litchfield and State of Connecticut, have invented a new, original, and ornamental Design for Corn Slitters, of which the following is a specification, reference being had to the accompanying drawing, forming part thereof.

Fig. 1 is a perspective view of a corn slitter showing my new design.

Fig. 2 is a transverse sectional view of the same taken through the thumb recesses.

I claim:

The ornamental design for a corn slitter as shown.

CAROLYN R. HANCHETT.
